HAND PROTECTOR

William Horlick, Jr., Racine, Wis.

Application February 12, 1931. Serial No. 515,300

3 Claims. (Cl. 20—16)

This invention relates to a hand protector for use in connection with sliding doors of various types, for example, a fire door which slides in a plane closely adjacent a wall, and which door 5 is provided with a hand-hole for facilitating manipulation of the door.

The objects of the invention are to provide an arrangement for preventing the fingers of a hand from being drawn between the wall and the door whereby they might be seriously injured; to provide a simple and inexpensive device of the type referred to, which will, nevertheless, be effective for its intended purpose; to provide such a device which will not unnecessarily 15 obstruct the doorway, and, in general, it is the object of the invention to provide an improved safety device of the class referred to.

Other objects and advantages of the invention will be understood by reference to the following 20 specification and accompanying drawing in which a selected embodiment of the invention is illustrated.

In the drawing:

Fig. 1 is a horizontal section through a portion 25 of a sliding door and the wall adjacent which the door slides, and

Fig. 2 is a perspective of the improved hand protector.

Referring now to the drawing, a sliding door 30 such as a fire door is indicated at 5, the door being of any suitable construction, such as metal, or of composite construction, and slidably mounted by any approved means not shown. Of course, it is understood that the door slides horizontally 35 in the direction of its width, as indicated by the arrow designated 6. The door, in this instance, is provided with a hand-hole 7 for facilitating manipulation of the door in a conventional manner and as indicated.

40 A wall portion adjacent which the door slides is indicated at 8, the arrangement being such that there is a small space, indicated at 9, between the door and the face 10 of the wall which is substantially parallel with the adjacent face of the door 5. The end face 11 of the wall 8 constitutes one side of the doorway which the door 5 closes.

It often occurs that a person opening a door arranged as above described inadvertently fails to withdraw his or her fingers from the hand-hole before the fingers are caught against the rear edge 12 of the hand-hole and forced into the restricted space 9 between the door and wall with resulting painful and often serious and permanent injury to the fingers.

55 For preventing such accidents, I provide a pro-

tector or guard, which, in this instance, comprises a non-metallic flexible flap-like portion 13, which projects into the doorway from the wall 11 at one side thereof, in such spaced relation to the door as to provide ample room between the door and the guard portion 13 to receive the fingers, as indicated in broken lines. It will also be noted that the guard member 13 projects into the doorway a sufficient distance to prevent the ends of the fingers from reaching the wall 8, and hence full protection is afforded.

The guard member 13, which may be made of leather, may be mounted on the wall in any suitable manner, and, in this instance, I have provided a base portion 14 consisting of an angle iron member having a side flange 15 to which the flexible guard portion 13 is secured by riveting, as indicated at 16, and a side portion 17 which is designed to be disposed against the side 11 of the doorway and secured thereto by means of bolts and nuts, as indicated at 18.

From an examination of Fig. 1 of the drawing, it will be understood that the flexibility of the guard portion 13 serves to permit yielding of the said portion away from the door when the guard is engaged by the fingers, whereby the width of the finger-receiving space may be readily increased to insure a sufficient amount of clearance between the fingers and the door. Also, such flexibility serves to facilitate withdrawal of the fingers without scraping them against the door. Another advantage incident to the use of the flexible portion 13 is that it may be made sufficiently flexible to be bendable to such an extent that it will not prevent the passage of large objects through the door.

By examination of Figure 2, it will be apparent that the length, i. e., the vertical dimension, of the guard is such that it will overlap the zone in which the hand will travel when manipulating the door through the agency of the hand-hole or other grip provided on the door. Obviously, the guard may be extended either vertically or horizontally to suit conditions of the particular installation for which it is intended. Of course, it will also be understood that the hand guard is applicable to vertical sliding doors wherever the arrangement is such that there is danger of injuring the hand in the manner described, and I consider such an installation within the terms of the appended claims.

I am aware that changes may be made in the details of construction of my improved hand guard without departing from the spirit of my invention.

invention, the scope of which should be determined by reference to the following claims.

I claim as my invention:

- 5 1. A guard for the purpose set forth, comprising a non-metallic flexible portion adapted to project perpendicularly into a doorway from a wall at one side thereof in such spaced relation to a sliding door closing said doorway and to such an extent as to provide finger-receiving space between the door and the flexible portion, and an 10 angular metal bracket member having a side portion to which said flexible member is secured in co-planar relation and a side portion adapted to be positioned against said wall for mounting the guard thereon.
- 15 2. In combination with a sliding door which slides in a plane closely adjacent and substantially parallel to a wall to close a doorway, a guard secured to the face of said wall within said doorway, said guard comprising an angular member having one flange attached to said wall and a flange projecting into said doorway, and a flex-

ible member secured to said last-mentioned flange and substantially co-planar therewith, said flange being spaced sufficiently from the face of said wall adjacent and parallel to said door to provide finger-receiving space between the door and said guard. 80

3. In combination with a sliding door which slides substantially parallel to and adjacent a wall surface, the door having manually engageable means adjacent its front edge for facilitating manual opening and closing of the door, a member secured to the wall adjacent the rear edge of the door and having a portion extending from the wall in the direction of and in spaced relation to the door, said member being of such length as to engage the hand or fingers of a person opening the door at a sufficient distance from the wall to prevent the fingers from contacting with the wall and being in such spaced relation relative to the door as to provide space for freely receiving the fingers. 85 90 95
